(57) **CLAIM**

The ornamental design for a bassinet mosquito net, as shown and described.

DESCRIPTION

FIG. 1 is a right perspective view of a bassinet, showing a first embodiment of our new design;

FIG. 2 is a front elevation view of the bassinet mosquito net of FIG. 1.

FIG. 3 is a rear elevation view of the bassinet mosquito net of FIG. 1.

FIG. 4 is a right elevation view of the bassinet mosquito net of FIG. 1.

FIG. 5 is a left elevation view of the bassinet mosquito net of FIG. 1.

FIG. 6 is a top plan view of the bassinet mosquito net of FIG. 1.

FIG. 7 is a bottom plan view of the bassinet mosquito net of FIG. 1.

FIG. 8 is a right perspective view of a bassinet, showing a second embodiment of our new design;

FIG. 9 is a front elevation view of the bassinet mosquito net of FIG. 8.

FIG. 10 is a rear elevation view of the bassinet mosquito net of FIG. 8.

FIG. 11 is a right elevation view of the bassinet mosquito net of FIG. 8.

FIG. 12 is a left elevation view of the bassinet mosquito net of FIG. 8.

FIG. 13 is a top plan view of the bassinet mosquito net of FIG. 8.

FIG. 14 is a bottom plan view of the bassinet mosquito net of FIG. 8.

FIG. 15 is a right perspective view of a bassinet, showing a third embodiment of our new design;

FIG. 16 is a front elevation view of the bassinet mosquito net of FIG. 15.

FIG. 17 is a rear elevation view of the bassinet mosquito net of FIG. 15.

(Continued)

FIG. 18 is a right elevation view of the bassinet mosquito net of FIG. 15.
 FIG. 19 is a left elevation view of the bassinet mosquito net of FIG. 15.
 FIG. 20 is a top plan view of the bassinet mosquito net of FIG. 15; and,
 FIG. 21 is a bottom plan view of the bassinet mosquito net of FIG. 15.
 In all figures, broken lines illustrate environmental structures and form no part of the claimed design.
